CLAIM

The ornamental design for a flexible fabric sleeve for bottle, as shown and described.

DESCRIPTION

FIG. 1 illustrates a top perspective view of a new and ornamental flexible fabric sleeve for bottle;
 FIG. 2 illustrates a bottom perspective view thereof;
 FIG. 3 illustrates a front view thereof;
 FIG. 4 illustrates a rear view thereof;
 FIG. 5 illustrates a left-side view thereof;
 FIG. 6 illustrates a right-side view thereof;
 FIG. 7 illustrates a top view thereof; and,
 FIG. 8 illustrates a bottom view thereof.
 The broken lines in the figures depict portions of the flexible fabric sleeve for bottle that form no part of the claimed design.
